UNITED STATES PATENT OFFICE.

RICHARD W. OWEN, OF MILWAUKEE, WISCONSIN.

DESIGN FOR LEATHER OR LIKE MATERIAL.

44,772.

Specification for Design.

Patented Oct. 21, 1913.

Application filed December 11, 1911. Serial No. 665,161. Term of patent 7 years.

To all whom it may concern:

Be it known that I, RICHARD W. OWEN, a citizen of the United States, residing at the city of Milwaukee, in the county of Milwaukee and State of Wisconsin, have invented a new, original, and ornamental Design for Leather or like Material, of which the following is a specification, reference being had to the accompanying drawing, forming part thereof.

The figure is a plan view of a piece of leather or like material showing my new,

original, and ornamental design applied thereto.

I claim:

The ornamental design for leather or like material substantially as shown.

In witness whereof I hereto affix my signature in the presence of two witnesses.

RICHARD W. OWEN.
